UNITED STATES PATENT OFFICE

2,488,774

BEACH AND LAND CLEANING MACHINE

Hussein V. Hassan, Bronx, N. Y.

Application August 12, 1944, Serial No. 549,168

3 Claims. (Cl. 55—17)

1

This invention relates to an improved machine for cleaning beaches and land, and one of its objects is to provide a machine which will raise surface portions of the sand of a beach, or of land, and cause such raised portions to pass through a separating screen, so that undesired debris or waste, like paper, broken glass, coins, paper money, jewelry, stones, and other objects, may be separated from the useful portions of the beach or land covering.

Another object of the invention is to provide a machine of this character which may be hauled by a motor or animal drawn vehicle, and which will maintain, while being moved over the beach or land, a rotary drum in motion, and which will operate to scoop up surface portions of the beach or land, and project them over an inclined screen, so that the finer particles will pass through the screen and the larger and undesired objects will drop through openings in the screen and be collected by a pan located under the screen.

Another object of the invention is the provision of a machine for this general purpose, with means for raising the excavating drum so that it will not engage the ground.

A still further object of the invention is the provision of a land and beach cleaning machine, with means for engaging and disengaging the excavating drum from driving gears or sprockets mounted on the rear axle, which is supported so that it will turn with the rear wheels.

With the above and other objects in view the invention consists in certain new and useful constructions, combinations and arrangements of parts, clearly described in the following specification, and fully illustrated in the accompanying drawings, in which:

Fig. 1 is a top plan view of the improved machine.

Fig. 2 is a side elevation thereof.

Fig. 3 is a rear end view, with the back body plate removed to expose the clutches and driving means.

Fig. 4 is a front end view thereof.

Fig. 5 is a detail side view of one of the levers used for raising the excavating drum.

Fig. 6 is a detail side view of the yoke used for this operation.

Fig. 7 is a detail plan view, on a reduced scale, of a draft tongue for coupling the machine to a motor driven vehicle.

Fig. 8 is a detail side view, on a reduced scale, of an excavating drum equipped with forked teeth.

2

Fig. 9 is a front view of the improved machine showing the location of the receiving pan.

Fig. 10 is a side elevational view of the front part of the machine shown broken away.

Referring to the accompanying drawings which illustrate the practical construction of my invention 5 designates a main frame, on the rear end of which the rear axle 6 is supported by the bearings 7 and 8. This rear axle is equipped with ground wheels 9 and 10, each of which is formed or provided with ground engaging cleats or teeth 11.

The forward end of the frame is supported by the front ground wheels 12 and 13, which are mounted by the pivot members 12a and 13a on the front axle 14, which is supported by the frame bracket lugs or members 15 and 16.

Forwardly of the rear axle an excavating drum 17 is arranged, which is provided with stub-shafts 18 and 19 on the ends thereof. These stub shafts project into the bearings 20, which slide between the arcuate guides 21 and 22, of the bearing plate 23. The bearings 20 are mounted on the forward ends of the levers 24, the rear ends of which are mounted directly on the rear axle, through the bearing 25, so as to permit the axle to turn without causing the levers to swing.

The excavating drum 17 is provided with a series of circumferentially spaced excavating buckets or members 26, which are designed to scoop beach sand or surface land covering and project it forwardly over the screen 27, which is inclined downwardly and forwardly from a point near the forward peripheral surface of the excavating drum.

The rear axle is equipped with sprocket wheels 28 and 29, which are not keyed thereto for rotation with the axle, and sprocket chains 30 and 31 transfer motion from the drive sprockets 28 and 29 to the driven sprockets 32 and 33 on the end shafts 18 and 19 of the excavating drum 17. The driven sprockets are considerably smaller than the drive sprockets, so that the excavating drum will rotate at a faster speed than the rear ground wheels turn.

The drive sprockets are provided with clutch elements in the form of spaced apart sockets 28a and 29a, which are adapted to receive the teeth 34a of the clutch element 34, and the teeth 35a of the clutch element 35, both mounted on the rear axle. These clutch elements are in the form of collars and are positively keyed to the rear axle so as to turn always with the rear axle. The clutch element 34 is provided with a ring 34b which is formed with a shifter groove 34c,

which is engaged by the stud pins 36 of the spanner shifter 37, which is pivoted to the cross bar 38. The clutch element or ring 35 is provided with a ring 35b, which is formed with a spanner groove 35c, and this groove is engaged by the stud pins 39 of the spanner 40, which is also pivoted to the cross bar 38.

A vertical lever 41 is pivoted to the cross bar 38, and is pivotally connected by the link 42 to the spanner 37, and is further pivotally connected by the link 43 with the spanner 40. By swinging this lever to the left, when in the position shown in Fig. 3, both clutches will be engaged, and motion will be transmitted from the rear wheels, through its axle, through the drive sprockets and chains to the driven sprockets of the excavating drum.

The excavating drum is raised by means of a yoke 44, which is pivoted at its ends to the levers 24, and this yoke is provided with an up-standing arm 45, which is pivotally connected to the lower end of the jack screw 46.

The jack screw 46 is mounted to turn on the standard or frame 47, which is mounted on the top plate 5a, and this screw is threaded to the head 48 of this frame 47. By turning the wheel 49 of the jack screw the yoke will be raised, as the lower end of the jack screw is swivelled to the arm 45 of the yoke, and the ends of this yoke are pivotally connected to the levers 24, which carry the drum bearings 20.

The tension of the sprocket chains may be regulated by means of the screws 51 and 52, which are threaded through the bar 50, which is fixed to the frame 5. The ends of the screws 51 and 52 engage the bar 53 of the sliding bearing plate 23, and by tightening or loosening the screws the bearing plate 23 may be shifted on the frame 5, which is in the form of a channel bar.

The screen 27 is provided with grooves 27c and 27d, which end with the discharge openings 27e and 27f, and auxiliary side screens 27a and a vertical front baffle screen 27b are provided for confining the movement of projected sand or earth over the separating screen 27. A pan P is arranged under the openings 27e and 27f, and these openings may be arranged on the side and buckets or receptacles provided for receiving the discharge thereof.

The excavating drum may be provided with curved prongs or tines 56, as shown in Fig. 8, on the drum 54, which is provided with the usual gear sprocket 55, shown conventionally.

The machine may be coupled to a vehicle by means of the draft tongue 57, and may be provided with a seat 58 at the rear end thereof. An engine or power plant may be also added for driving the rear axle by a sprocket transmission.

Various changes in the details of construction and arrangement of parts may be resorted to, without departing from the scope of the invention, as defined in the claims hereof.

Having described my invention I claim as new:

1. A land cleaning machine, consisting of a main frame, a forward axle supported on the

frame, ground wheels on the ends of the axle, a rear axle mounted to turn on the frame, ground wheels mounted on the ends of the axle to turn therewith, sprocket gears mounted to turn on the rear axle, clutches for coupling the sprocket gears to the rear axle, means for simultaneously operating both clutches, an excavating drum mounted to turn on the main frame, said excavating drum having curved land digging blades, sprocket gears on said drum, chains engaging the gears of the rear axle and the drum gears for transmitting motion from the rear axle to the drum gears, a separating screen mounted on the main frame and inclined from a point near the drum to the forward end of the machine, said screen having an opening located at the lowest end thereof, and a receptacle located below said opening.

2. A land cleaning machine, consisting of a wheeled frame, rear ground wheels for the frame, forward ground wheels for the frame, a rotary excavating device mounted to turn on the frame between the forward and rearward wheels, a screen mounted on the frame forwardly of the excavating device and inclined downwardly and forwardly thereof, and provided with discharge openings near its lower end, a pan for receiving material discharged through the said openings, and means for driving the rotary device from the rear wheels.

3. A land cleaning machine, comprising a frame, a wheeled front axle therefor, a wheeled rear axle therefor, gear means coupled to said rear axle, a rotary drum mounted to turn on the frame and provided with curved ground penetrating blades, means coupled to said gear means for rotating said drum to project ground rearwardly thereof when the drum is rotated, a screen inclined downwardly and rearwardly from the drum and located to receive ground projected by the rotation of the drum, means coupled to said frame and said drum at the rear of said frame for raising and lowering the drum to vary the depth of penetration of the blades thereof, said screen having a discharge opening located at the lowest part thereof for the discharge of large objects, a receptacle located below said screen discharge opening, and an upright baffle screen located at the front edge of the inclined screen.

HUSSEIN V. HASSAN.
